PENCIL SHARPENER STAND

Harry Preble, Cross River, and Joseph Rubinstein, Newburgh, N.Y., assignors to General Slicing Machine Co., Inc., Walden, N.Y., a corporation of New York

Filed Mar. 27, 1964, Ser. No. 79,234

Term of patent 14 years

(Cl. D74—21)

FIG.4

FIG. 1 is a perspective view of a pencil sharpener stand embodying our new design;

FIG. 2 is a side elevation thereof partly in section, the broken line illustration in this view only of the handle, shavings cup and base being for illustrative purposes;

FIG. 3 is a top plan view of the pencil sharpener stand shown in FIG. 1;

FIG. 4 is a rear view thereof;

FIG. 5 is a front view thereof;

FIG. 6 is a section taken at lines 6—6 in FIG. 2.

We claim:

The ornamental design for a pencil sharpener stand, substantially as shown and described.
